UNITED STATES PATENT OFFICE.

MARTIN M. MATSON AND CHARLES M. MATSON, OF MADISONVILLE, OHIO.

MECHANICAL MOVEMENT.

Application filed April 24, 1926. Serial No. 104,367.

This invention relates to mechanical movements and more specifically to one suitable for use in connection with a rocking chair.

The object of this invention is to utilize 5 to some useful purpose the unused energy created in a rocking chair. To convert this energy to a useful purpose requires a particular movement wherein lies this invention.

The novelty of the movement lies chiefly 10 in obtaining a continuous rotation out of an initial movement which is but semi-rotatable.

Further novelty lies in the simplicity and the efficiency of the movement.

Other novelty will be disclosed in the 15 description and drawings.

Figure 1 is a side elevation of the movement attached to a rocking chair operating a fan;

Figure 2 is a front elevation of the movement attached to operate a fan;

Figure 3 is a sectional view taken through line E E of Figure 2;

Figure 4 is an elevation of the rocker arm shown on back of Fig. 1, and

Figure 5 is a vertical view partly in section of a portion of the mechanism.

Figure 1 shows the invention comprising a semi-circular disk 1 pivotally connected at 2 to a support 3 which in turn is attached 30 to a rocker 4. Attached to disk 1 at 5 is a push rod 6 which in turn is held in place by brace rod 7 attached to the rocker 4 at one end and to the rocker arm 6 at the other.

A spring 8 is also attached to the end of 35 semi-circular disk 1 and rocker arm 6. A cord 9 attached at one end of semi-circular disk 1 passes over the faces of corresponding pulley 10 to a pulley 11 set at right angles to pulley 10 and from there around a pulley

40 12, back around a pulley similar to 11 called 11' and from there over a pulley 10' to opposite end of semi-circular disk 5 from which it started. 10 and 10' are mounted on an oscillating arm 20. Rollers 11 and 11' are

45 mounted in a housing 13 and 13' respectively, which are pivotally mounted on arm 14. Extending from the housings as shown in Figure 3 is a spring arm 15 which rests on a pivoted rocker arm 16 as shown in Figure

50 4. Directly below pulleys 11 and 11' respectively, are rubber disks 17 and 17' as shown in Figure 3. These disks are mounted on a shaft 19 on which in turn is mounted a fan 21. Attached to spring arms 15 and 15' are cords 18 and 18' attached to the base of

55 pulleys 10 and 10' respectively, a pin 22

passing through rocker arm 16 in its middle section so that the rocker arm 16 may oscillate according to where the pressure is exerted by spring arm 15 or spring arm 15'. 60

In operation, as the rocking chair comes forward, the push rod 6, coming in contact with a surface, causes the disk 1 to tilt downwardly and the cord 9, to bear against pulley

10' which in turn causes the oscillating arm 20 to tip downwardly. The cord 18' which is attached to pulley 10' exerts a downward pull on spring arm 15' which in turn causes

housing 13' containing roller 11' to tilt downwardly and engage rubber disk 17. 70

Rubber disk 17' is mounted on a shaft 19 on which is likewise mounted fan 21. When roller 11' comes into contact with rubber

disk 17', it causes the fan 21 to revolve. As soon as the rocker reaches the end of its forward movement, the force ceases to be exerted counter-clockwise and the spring 8 exerts a force against the roller 10, thus tilt- 75

ing the arm 20 in the opposite direction and bringing pulley 11 into contact with rubber

disk 17. By this manipulation pulley 11' is thrown out of contact with disk 17' and thus the fan is kept continuously revolving by an oscillating movement of the disk 1, thus over- 80

coming the difficulty of carrying a lever past

such a movement.

Claims:

1. In a mechanical movement a rotary member, a plurality of driving members on the rotary member, a flexible member, driving members adapted to be driven by the flexible member and to engage the driving members on the rotary member, means for selectively engaging the last mentioned driving members with the driving members on the rotary member. 90

2. In a mechanical movement a rotary member, a plurality of driving members on the rotary member, a flexible member, driving members adapted to be driven by the flexible member and to engage the driving members on the rotary member, means for guiding the flexible member in a loop above

100 the rotary member, means for selectively engaging the last mentioned driving members with the driving members on the rotary member. 105

3. In a mechanical movement a rotary member, a plurality of driving members on the rotary member, a flexible member, driving members adapted to be driven by

the flexible member and to engage the driving members on the rotary member, the flexible member passing over the driving members in the form of a loop, the loop encircling a bearing at right angles to the driving members, means for selectively engaging the last mentioned driving members with the driving members on the rotary member.

10. 4. In a mechanical movement a rotary member, a plurality of driving members on the rotary member, a flexible member, driving members adapted to be driven by the flexible member and to engage the driving members on the rotary member, two rocker members pivoted on a shaft, the flexible member passing over bearings mounted on the lower rocker member and driving members on the upper, rods attached to the said bearings in such a manner that when the flexible member bears against the outer face of the bearing mounted on the lower rocker member, the rocker member will be tilted, thus bringing the tilted driving member on the upper rocker member into contact with the corresponding driving member on the rotary member, upon the flexible member ceasing to bear against the outer bearing, the rocker members will return to their former position, thus bringing the other driving member into contact with the respective driving member mounted on the rotary member.
25. 5. A fan attachment for rocking chairs comprising a frame adapted to be secured to

the frame of a chair, a shaft mounted in the frame, a fan on the shaft, two friction drive pulleys mounted on the shaft, a second shaft mounted in the frame parallel with the first two rocker members pivoted on the second shaft and extending over the drive pulleys on the first shaft, a pulley mounted in each rocker member constructed to guide a flexible member and also to drive one of said friction drive pulleys when in contact therewith, a rocker lever provided to the frame intermediate the said rocker member and extending transversely of and beneath the free ends of said rocker members, a second rocker lever parallel with the first, guide rollers, one on each arm of said second rocker lever, links connecting the arms of said second rocker lever with the arms of the first rocker lever, a double armed lever pivoted to the frame of the chair adjacent the rocker thereof, a flexible member having its ends secured to the ends of said double armed lever, means for guiding the flexible member in a loop through the frame and over the pulleys in said rocker members, and a ground contacting member pivoted to one arm of the double armed lever whereby the rocking of the chair will oscillate said double armed lever, reciprocate the flexible member and rotate the fan substantially as specified.

In testimony whereof we affix our signatures.

MARTIN M. MATSON.
CHARLES M. MATSON.
